UNITED STATES PATENT OFFICE.

JOHN K. NORTHRUP, OF SAWTELLE, CALIFORNIA.

FLUSHING TANK.

Application filed April 25, 1925. Serial No. 25,918.

My invention relates to a flushing tank and particularly to an automatically operated tank adapted for use in flushing sewers.

An object of the invention is to provide a flushing tank of such extreme simplicity of structure and operation that it does not require lubrication or servicing.

A further object of the invention is the production of a flushing tank which may be installed in a manhole of standard construction.

My invention comprises other objects which with the foregoing will be set forth in the following description of the preferred embodiment of means for practicing the invention which is illustrated in the drawings accompanying and forming part of the specification. It is to be understood that I do not limit myself to the showing made by the said description and drawings as I may adopt variations of my preferred form within the scope of my invention as set forth in the claims.

Referring to the drawings:

Figure 1 is a horizontal sectional view taken on the line 1-1 of Fig. 2.

Figure 2 is a side elevation of my flushing tank and its mounting arranged in a manhole of standard construction.

Figure 3 is a diagrammatic view showing the various centers, and the path of movement of the center of gravity as the tank is filled.

Broadly, my invention comprises a drum having a discharge opening in the top of the empty upright drum, and a lip edging one side of the discharge opening to permit the accumulation of an unbalancing load. The drum is mounted for free rotary movement about a horizontally disposed axis which is spaced above the center of gravity of the empty upright drum. Means are provided to fill the drum with water and as it approaches full load, the unbalancing load included within the lip increases until it tips the drum, causing it to roll on its axle, which is seated on a suitable mounting secured in the walls of the manhole. As the load discharges the center of gravity shifts so that the empty drum returns automatically to the upright position, where it is again refilled and the cycle repeated indefinitely.

The operation of my flushing tank is not dependent upon valves, gauges or other similar devices so that pebbles, small sticks or other small objects will not interfere with

its perfect operation. The simplicity of the structure practically obviates the necessity of servicing which is a costly item with the types of flushing tanks now in use.

In detail, my invention comprises a drum 6, preferably cylindrical in shape, and of such size as to accommodate 150 to 200 gals. of water which is the amount required for most flushing purposes. In practice I have found it desirable to make the drum in parts so that it can be passed thru the opening and assembled in the larger portion of a standard manhole. For example, the ends 7 and 8 may be formed in two pieces which may be secured together in any suitable well-known manner such as welding or riveting; the side may comprise a single sheet of metal which can be rolled up to permit it to be placed in a manhole having the usual 22 inch opening. When the drum has been assembled it may be given a coating of asphaltum or similar material to prevent rust and seal the joints so that the danger of leaks will be removed.

A discharge opening 9, of less width than the diameter of the drum, is provided at the top of the empty drum; and edging one side of this opening is a lip 11 in which an unbalancing load is accumulated, as the tank is filled with water provided by means of a suitable inlet 12 controlled and regulated by the valve 13.

A shaft or axle 16 extends thru the upright drum, the axis of the shaft preferably lying vertically above the center of gravity and slightly above the horizontal plane passing thru the geometric center line of the drum. The shaft is spaced a little toward the lip side of the vertical plane passing thru the geometric center line of the drum. This off-center position compensates for the additional weight of the metal in the lip and causes the empty tank to assume a position in which the lip side of the discharge opening is slightly higher than the opposite side. Due to the large amount of metal removed from the top of the drum to form the discharge opening the center of gravity of the empty upright drum is lowered, and this permits the placing of the axle above the center of gravity so that the empty drum will always return to upright position. The placing of the shaft 16 as just indicated produces the most satisfactory results, but slight variations may be made without changing the operation of the device. One

of the most advantageous features of this flushing tank is the low cost of production and this is partly dependent upon a certain amount of leeway permissible in its construction.

Each end of the axle 16 passes thru a flanged collar 17 fixed to the drum end, and terminates in a journal 18. The collar prevents the sides of the drum from contacting with the supporting beam 21 on each side of the drum. The supporting beams are preferably of I-beam type, and have each end embedded in the masonry 22 of the man-hole. The journals roll on these beams and the rolling movement is limited by the stops 23 and 24 which are fixed to the beams and spaced apart a distance less than the longitudinal rolling movement of the journals if free. The spacing of the stops is such that the rolling movement of the drum is converted into a rotary movement about the axle when the journals strike the stops. These stops further operate to prevent racking of the drum, for if one journal strikes a stop before the other, the momentum of the drum forces the shafts back into proper alignment. The seat 26 formed by the stops 23 and 24 with the journal 18, constitutes a rolling bearing which requires no lubrication and the operation of which is not impaired by the presence of foreign matter, since the latter is crowded off the seat by the movement of the journals thereon.

The operation of my flushing tank is as follows.

The drum in upright position is filled with water from the pipe 12. By referring to Fig. 3, it will be noted that the center of gravity of the empty upright drum is indicated by the point marked I. As the drum is filled, the center of gravity drops in a vertical line 25 to the point indicated by the character II. The drum maintains its slightly tilted position until the water reaches the level at the base of the lip when it gradually rights itself and remains in practically upright position until the water is within three or four inches of the top of the drum. As the level of the water rises the center of gravity rises in the same line 25 until the water begins to fill the lip 11 in which the unbalancing load accumulates. At this point the center of gravity begins to shift gradually toward the lip until, when the drum has a full load, the center of gravity has shifted thru the line 27, to the point indicated by the character III, and the unbalancing load is sufficient to start the drum tipping. This slight movement is accelerated by the flow of the water to the discharge side so that the drum is rapidly turned to full discharge position. The first movement of the drum is a rolling movement in which the journals progress horizontally along the seat 26 until the stops 23

are encountered. The movement is then converted into a rotary movement about the shaft 16 until the momentum is lost. The water flowing from the lip provides a heavy upsetting force which aids in maintaining the drum in inverted position until the entire load has been discharged. When discharging is complete, the center of gravity shifts back to its original point, and the drum automatically returns to equilibrium in its upright position. Because of the friction of the journals turning against the stops, they act as brakes at both ends of the movement of the drum so that violent action and continued rocking of the drum is prevented. The operation of my device is therefore silent, and is not accompanied by sudden shocks or stresses which would damage the structure or cause appreciable deterioration or wear therein.

When the tank regains its upright position the cycle of operation has been completed, and the accumulation of the next load begins. It will be obvious that by adjustment of the valve 13, the time in which the drum fills, and therefore the interval between successive actions, may be closely regulated, so that the drum may be made to discharge its load every two hours or every two days, as requirements may dictate. Once set, the operation continues indefinitely and entirely automatically at the desired interval, without the need of any attention.

I claim:

1. A flushing tank comprising a cylindrical drum mounted for rolling and free rotary movement and with the cylindrical axis in horizontal position, and having a discharge opening on one side above the center of gravity when the tank is empty, means for filling the drum, and means for permitting the accumulation of an unbalancing load as the drum approaches full load.

2. A flushing tank comprising a cylindrical drum mounted for rolling and free rotary movement and with the cylindrical axis in horizontal position, and having a discharge opening on one side above the center of gravity when the tank is empty, means for filling the drum, and a lip edging the discharge opening for permitting the accumulation of an unbalancing load as the drum approaches full load.

3. A flushing tank comprising a cylindrical drum mounted for free rotary movement and with the cylindrical axis in horizontal position, and having a discharge opening on one side above the center of gravity when the tank is empty, means for filling the drum, means for permitting the accumulation of an unbalancing load as the drum approaches full load, and a mounting on which said drum rolls as its tips to discharge its load.

4. A flushing tank comprising a cylin-

drical drum mounted for free rotary movement and with the cylindrical axis in horizontal position, and having a discharge opening on one side above the center of gravity 5 when the tank is empty, means for filling the drum, means for permitting the accumulation of an unbalancing load as the drum approaches full load, a mounting on which said drum rolls as it tips to discharge 10 its load, and stops on said mounting to control the rolling movement of the drum.

5. A flushing tank comprising a drum, a supporting beam on each side of the drum, a seat on each beam, and a journal fixed on 15 each side of the drum and adapted to roll transversely on said seat.

6. A flushing tank comprising a drum, a supporting beam on each side of the drum,

journals fixed on the sides of the drum and adapted to roll transversely on said beams, 20 and a stop on each beam on each side of each journal, the stops on each beam being spaced apart a distance less than the longitudinal rolling movement of the journals if free.

7. A flushing tank comprising a freely 25 mounted drum having the center of gravity below the rotational axis, and provided with a side lip portion for holding an unbalancing load so that the center of gravity of the full drum is shifted from a point vertically 30 below the rotational axis to a point to one side of said axis.

In testimony whereof, I have hereunto set my hand.

JOHN K. NORTHRUP.
